UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

HOT TOP FEEDER FOR INGOT MOLDS.

Application filed April 24, 1924. Serial No. 708,685.

To all whom it may concern:

Be it known that BLOOMFIELD H. HOWARD and ERNEST J. TURNER, citizens of the United States, residing, respectively, at Washington, District of Columbia, and Pittsburgh, in the county of Allegheny and State of Pennsylvania, have invented certain new and useful Improvements in Hot Top Feeders for Ingot Molds, of which the following is a specification.

Our invention relates to improvements in hot top feeders for ingot molds.

The object of our invention is to provide a feeder for ingot molds made of refractory material and adapted to be inserted in the mold and supported by the upper end thereof and at the same time provide a feeder having the necessary material above the mold to retain the heat and to prevent what is known as "piping" and to reduce "segregation."

Another object of our invention is to provide a feeder for ingot molds having means whereby it may be supported on the upper end of the mold with either end in the mold whereby ingots of different lengths may be cast with the same feeder, all of which is well understood by those skilled in the art.

A further object of our invention is to provide a simple, cheap and effective feeder adapted to accomplish these results and having certain details of structure and combination of parts hereinafter more fully set forth.

In the accompanying drawings:

Figure 1 is a perspective view of an ingot mold showing our improved feeder applied thereto.

Figure 2 is a top plan view of Figure 1.

Figure 3 is a transverse vertical sectional view showing a reversible feeder embodying our invention.

In the accompanying drawings 1 represents the mold which as is understood may be of any desired shape and 2 is the improved feeder which is of a shape to correspond with that of the bore of the mold and adapted to enter the same. As shown in Figure 1 of the drawings the upper end of the mold is provided around its outer surface with an annular flange 3 which provides for sufficient refractory material at the upper end of the feeder to retain the heat so that the upper end of the ingot will

not cool rapidly, all of which is well understood and needs no further description. This flange 3 is provided with a number of vertically disposed grooves 4 which in turn form the rectangular shaped ribs 5 which are adapted to support the feeder on the upper end of the mold. It will be seen that the vertically disposed grooves 4 do not have their inner ends intersecting the body portion of the feeder and therefore the body portion is not weakened by the grooves.

The vertically disposed ribs 5 as shown in Figure 1 together with the semi-circular inner wall 6 of the groove 4 cover the entire outer wall of the feeder and this greatly strengthens that portion of the feeder above the mold, which portion is that subjected to the greatest strain.

In the modification shown in Figure 3 we have provided the feeder 7 intermediate its ends with the annular flange 8 similar to that shown in Figures 1 and 2 of the drawings. This flange like that shown in Figures 1 and 2 of the drawings is provided with the vertically disposed grooves 9 forming the rectangular ribs or projections 10. By this structure it will be seen that we have provided a reversible feeder, the flange being nearer one end of the feeder than the other. By reversing the feeder the same will extend a greater or less distance into the mold for casting ingots of different lengths.

Having thus fully described our invention what we claim is:

1. A feeder for ingot molds comprising a body portion having a series of rectangular connected ribs extending entirely around the same.

2. A feeder for ingot molds comprising a body portion having a flange extending around the same and having vertically disposed grooves forming rectangular ribs.

3. A feeder for ingot molds comprising a body portion of refractory material having a series of connected rectangular ribs extending around the same.

4. A feeder for ingot molds comprising a body portion of refractory material having an annular flange extending around the same and having a series of vertically disposed grooves with curved inner walls forming ribs the outer faces of which are

5. A feeder for ingot molds comprising a body portion of refractory material having a series of connected ribs extending entirely around the body portion intermediate its ends.

6. A feeder for ingot molds comprising a body portion of refractory material hav-

ing a flange extending around the outer surface intermediate its ends and having vertical grooves therein.

In testimony whereof we affix our signatures.

BLOOMFIELD H. HOWARD.
ERNEST J. TURNER.
